UNITED STATES PATENT OFFICE

WINTHROP K. HOWE, OF ROCHESTER, NEW YORK, ASSIGNOR TO GENERAL RAILWAY SIGNAL COMPANY, OF ROCHESTER, NEW YORK

TRAIN CONTROL

Application filed October 29, 1924. Serial No. 746,578.

This invention relates to automatic train speed control systems for railways, and more particularly to such systems of the so-called continuous inductive control type.

Generally stated, the system of this invention automatically applies the brakes at each caution signal or corresponding control point and prevents the release of the brakes until the train has been brought to a stop, unless the engineer takes suitable anticipatory action, conveniently called acknowledgment. The engineer is also required to acknowledge near the exit end of the caution block, braking distance for the minimum speed from the stop signal at the entrance to the next block in advance. In accordance with this invention, the engineer is required to acknowledge each successive stop signal.

As the train travels through a caution block, the brakes are automatically applied unless the speed of the train is reduced and at all times is within a curve of permissive speed limits, thereby assuring that the train at all times can be stopped before reaching the end of the caution block. For this purpose brake control apparatus of the speed-distance type is preferably employed, such as illustrated, for example, in the patent to P. J. Simmen, No. 1,150,308, dated August 17, 1915. In the continuous inductive type of train control system, as ordinarily installed, the car relay is deenergized momentarily at various points along the track, conveniently called "dead sections," frequently found at frogs, cross-overs, staggered insulated joints, and similar locations; and it is proposed to use the distance element of the regular speed-distance type of speed control apparatus to permit train movement over such dead-sections without automatic brake applications or the need for acknowledgment.

Occasionally dangerous conditions of the trackway ahead arise suddenly, such as the opening of a switch improperly, the breaking of a track rail, or the like; and since the continuous inductive type of control immediately manifests upon the following train such sudden change to danger, it is proposed in accordance with this invention to organize the brake control apparatus such that a minimum

speed limit, or equivalent safe control, will be instantly and automatically set up in the event of such sudden danger, it being beyond the power of the engineer, by acknowledgment or otherwise, to prevent such minimum speed limit or avoid a brake application as the result of this speed limit.

In addition to the regulation of the speed of trains to enforce obedience to the indications of block signals, it is desirable to enforce an absolute stop at certain points, such as at drawbridges, crossings, and the like. For this purpose it is desirable to have an indication or control from the trackway, in addition to those used for governing the trains in automatic block signal territory, and provide for an automatic unpreventable brake application, occurring irrespective of speed, upon failure of such additional indication or control. In accordance with the present invention, it is proposed to maintain a signalling or train control current on the track rails throughout block signal territory, irrespective of traffic conditions, and to utilize cessation of such current at the interlocked signal or corresponding point of absolute stop to produce the desired brake application.

Various other objects, advantages, and characteristics features of the invention will be in part apparent and in part pointed out as the description progresses.

In describing the specific embodiment of the invention illustrated in detail reference will be made to the accompanying drawings in which:—

Fig. 1 shows in a simplified and diagrammatic manner the trackway equipment of an automatic train control system of this invention for automatic block signal territory, together with the impulse receiving equipment and main control relay on the car, speed-distance curves of permissive speed and train performance, and interrupted lines indicating the points of opening and closing of certain contacts;

Fig. 2 illustrates how the same track which has been shown in Fig. 1 is modified and organized to provide for speed control and an absolute stop upon the approach to an interlocked signal;

Fig. 3 illustrates in a simplified and diagrammatic manner the operating gearing and associated parts, forming part of the car apparatus, which provides for the control of speed-distance contacts, distance contacts, and speed contacts;

Fig. 4 illustrates diagrammatically and according to certain arbitrary conventions the various parts of the car apparatus and their circuit connections, this figure constituting in effect a wiring diagram of the car-carried apparatus; and

Fig. 5 illustrates a modified form of the trackway equipment for block signal system territory and for the approach to an interlocked signal, together with curves and interrupted lines, similar to those shown in Figs. 1 and 2.

Trackway equipment.—Figs. 1 shows the usual type of control circuits and devices for a continuous inductive control system of the three-position type having direct current track circuits. The track rails 1 are divided into blocks by insulating joints 2 in the usual way, one complete block I and the adjacent ends of two other blocks H and J being shown. For simplicity it is assumed that the length of these blocks corresponds to braking distance and includes only one track circuit, various expedients (not shown) being employed to adapt the system to blocks of various lengths and those including cut sections. It is also assumed that all of the blocks will be equipped the same, so that a description of one will suffice for all.

Using the reference numbers of the block I, each block is provided with a normally closed direct current track circuit, including a track battery 3 and a track relay 5. The track phase or loop circuit current for the train control system, which flows in opposite directions in the track rails at a given instant, is impressed across the track rails at the exit end of each block by a transformer 4, having its secondary in series with the track battery 3, and its primary continuously energized from a line transformer 6 connected to the usual transmission line T. The line phase or simplex circuit current, which flows in the same direction in the two track rails at a given instant, is supplied to the track rails of each block through balancing resistances 7 and 8 across track rails at the ends of the block, the middle points of these resistances being connected by line wires 9 and 10 to contact fingers 11¹ and 12¹ of the track relay 5¹ of the next block in advance and through pole-changing contacts 11¹ and 12¹ to the secondary of a line transformer 13¹. The line phase and track phase currents are displaced in phase in the usual way.

While the present train control system may be used with or without wayside signals as desired, semaphore signals Z have been

shown conventionally without attempting to illustrate their well known control circuits and devices.

Figure 2 shows the trackway equipment for a block K next in the rear of an absolute stop and stay signal, ZA, which is assumed to be controlled manually from a tower by an interlocked lever in the usual way, with such locking and well recognized expedients as may be found desirable. In this block K of absolute stop control, an additional balancing resistance 14 is connected across the track rails a short distance from the exit end thereof; and provision is made so that, with the stop and stay signal ZA in the stop position, the line phase or simplex current is supplied between the balancing resistance 7² at the entrance to the block K and the balancing resistance 14 only, there being no line phase or simplex circuit current for the short distance at the exit end of the block. In the simplified form of the invention illustrated, a switch 15, assumed to be connected to or operated by an interlocked lever or equivalent means, is used to control the connection of the line phase circuit to the resistances 14 and 8². When the signal ZA is at stop, it is desirable to enforce restricted speed limits upon its approach; and as shown, this is accomplished by pole changing contacts 16 on the signal ZA controlling the line phase current.

Car equipment.—The receiving devices for detecting and amplifying the train control current in the track rails are, generally speaking, of the usual type and construction. Referring to Fig. 1, the locomotive and tender or other vehicle, is represented by the wheels and axles 19, and receiving coils 20 in front of the first axle and wheels are resonated by a condenser 21 and connected to the input circuit of an amplifier TA, the output circuit of which is connected to one field winding 22 of the main car relay MR. Other coils 23 in the rear are similarly resonated by a condenser 24 connected to an amplifier LA, and to the other field winding 25 of the relay MR. The front and rear coils are wound and connected in the usual way so as to be responsive respectively to the track phase current and the line phase current. The car relay MR is of the usual two element rotor or vane type and operates its contact fingers to any one of three different positions in accordance with the presence and phase relation of the track phase and line phase currents or absence of either, in the usual way.

In addition to the relay MR, another relay LR is connected to the output of the line phase amplifier LA, this relay LR being either of the single phase alternating current type, or, if an extra rectifying tube is used, this relay may be a direct current sensitive relay of the tractive type.

Referring to Fig. 3, the gearing and associated devices diagrammatically illustrated

are similar in many respects to that shown in my prior application, Ser. No. 38,132 filed July 2, 1915. The shaft 28 is operatively connected to an axle of the locomotive or other vehicle by suitable means not shown and drives a speed responsive device SD, which is shown in a simplified and conventional manner as of the usual centrifugal type, acting to move a collar 29, downward in opposition to a spring 30 as the speed increases and thereby rocking a speed shaft 31, through a connecting arm 32, to different angular positions in accordance with the running speed. The speed shaft 31 is used to open and close contacts throughout different rates of speed.

A typical speed contact unit is shown in Fig. 3, and comprises an actuating sector 33 secured to the speed shaft 31 and having its outer edge formed with two concentric curved portions of different radii, connected, connected by an inclined portion constituting an operating shoulder. A roller secured to a resilient or spring-pressed contact finger 34 bears against the edge of the actuating sector; and in the form of speed contact fingers shown in Fig. 3, the contact finger 34 is forced by the operating shoulder on the sector 33 against a stationary insulated contact 35, indicated by an arrow, when the running speed is 15 miles per hour or less. It will be evident that the edge of the contact actuating sector 33 may be shaped to provide for the opening or closing of contacts throughout any desired range of speeds.

The car apparatus includes two distance element operating shafts 36 and 37; but since these elements are constructed substantially the same, a description of one will suffice for the other, the same reference characters with distinguishing exponents being used. A worm 38 on the shaft 28 drives a gear 39, a shaft 40 a pinion 41, and a gear 42. A pinion 43, constantly in mesh with the gear 42, is carried by a swinging arm 44 pivoted on the axis of said gear; and this pinion 43 moves into and out of mesh with a gear 45 as the arm 44 is raised or lowered, said gear 45 having a mutilated or cut-away portion 46 for the purpose hereinafter explained. The arm 44 is urged to its upper position by a spring 47 to bring the pinion 43 into mesh with the gear 45 and is held in its lower position by a cam starter magnet HCS. The gear 45 is fastened to the distance shaft 36 (and 45¹ is similarly fastened to 37) which is biased to a predetermined initial position shown by a spring 48, anchored at one end and connected at the other end to a short crank arm 49 fixed to said shaft.

The distance shaft 36 drives a permissive cam 50. A roller on the upper end of a floating lever 51 engages the edge of this cam 50; and the lower end of this floating lever is pivotally connected to an arm 52 fixed on the speed shaft. An intermediate point of

the floating lever 51 is connected by a pivoted link 53 to an actuating sector 54 which is rocked by a spring 55 in a direction to press the roller on the lever 51 against the cam 50. This actuating sector 54 and its contacts 56 are constructed similar to those already described, and act to open the contacts when the middle point of the floating lever assumes a predetermined position to the left.

The cam 50 is shaped, with regard to the angular movement of the associated parts, so that when moved gradually by the car wheels, the contacts 56 open at different speeds for different locations of the train in the block in conformity with a speed distance curve of permissive speed such as the curve 57 shown in Fig. 1, the way in which this result is obtained being explained more in detail in my prior application above mentioned.

Each of the distance elements or shafts 36 and 37 is used to open or close contacts at predetermined points of travel of the train. A typical distance contact is shown in Fig. 3, and comprises an actuating cam disc 58 and a pair of contacts 59 biased apart, said contact disc being provided with recesses and shoulders extending over different arcuate portions of the disc, so as to open or close the contacts at the desired point in the rotation of the corresponding distance shaft.

In addition to the operating gearing and contact units shown in Fig. 3, the car apparatus includes a suitable brake control device. Since the particular brake applying means forms no part of the present invention, a conventional form of electro-pneumatic valve EPV has been illustrated to facilitate explanation of the manner of control of the brakes, it being assumed that the automatic brake applying mechanism will be controlled by an electro-pneumatic valve and will be actuated whenever this valve is de-energized.

The car apparatus also includes an acknowledging contactor AC, which in the form shown comprises a push button or plunger 61, urged by a spring 62 to the upper position shown, and carrying insulated contact discs 63 and 64 arranged to engage stationary contacts shown conventionally by arrows. An armature 65 is fastened to this plunger 61, and when the plunger is in its lower position, and a magnet 66 is energized, the plunger 61 will be held down against the opposition of the spring, 62. The magnet 66, however, is not strong enough to pull the plunger 61 down. For purposes more fully explained hereinafter, an emergency non-control contactor N is also provided; and in the simplified form shown, this contactor comprises a simple push button or key 67, inclosed within a locked or sealed casing indicated by the dash lines. The car apparatus

also includes an acknowledging relay AR, a non-control relay NC, a penalty relay PR, and suitable cab signals or indicators. These cab signals are shown for simplicity as consisting of electric lamps of different colors; but these signals may take any suitable form, visual or audible, one construction preferred for ordinary uses comprising a lamp behind a glass screen which causes letters or other distinctive insignia to stand out, plain or colored, when the lamp is lighted.

Fig. 4 shows the electrical connections between the various devices of the car apparatus; and in this circuit plan, various conventions have been adopted to simplify the illustration and facilitate explanation. The contact fingers of the various relays are shown directly under the conventional illustration of the windings, the several fingers for each relay being connected by dash lines. The cam controlled speed contacts 34—35 and 68—69 are shown connected by a dash-and-dot line representing the speed shaft 31; and the cam controlling the two groups of distance contact units 59, 70 and 71, 59¹, 72, 73 and 74 are similarly shown above each other connected by dot-and-dash lines. At the left and right of Fig. 4 are bus wires 75 and 76 connected to the opposite terminals of a battery 77, turbo-generator, or other suitable source of car-carried energy; and the circuits will be traced hereinafter from one bus to the other.

Operation

The car relay MR moves its contact fingers to one extreme position, shown in full lines in Figs. 1 and 4, while the train is traveling in a clear block, shifts these contacts to the opposite extreme position in a caution block, and permits these contact fingers to assume the biased vertical position in a danger block, this operation being typical of the three-position type of continuous inductive control system shown and requiring no further explanation. The line phase relay LR is maintained energized, except at the dead-sections, throughout block signal territory, and is de-energized only at approach to an absolute stop signal.

Fig. 4 shows the parts and circuits of the car apparatus their normal initial condition corresponding to the movement of the train in a clear block at some intermediate speed higher than the minimum speed, assumed to be 15 miles per hour, and lower than the maximum speed, assumed to be 60 miles per hour. In the normal condition of the car apparatus, the green or proceed cab signal G is energized and illuminated by a circuit which may be traced as follows:—Beginning at the positive bus 75, wire 86, finger 87 of the relay MR and its normal contact, wires 88 and 89, finger 90 of relay NC and its back

contact, wire 91, lamp G, and wire 92 to the negative bus 76.

The cam starter magnet HCS is energized by a circuit which may be traced as follows:—Beginning at the positive bus 75, wire 86, finger 87 of relay MR and its normal contact, wires 88 and 93, cam starter magnet HCS, wire 94, finger 95 of relay AR and its back contact, and wire 96 to the negative bus 76.

The other cam starter magnet LCS is energized by a circuit which may be traced as follows:—Beginning at the positive bus 75, wire 97, finger 98 of relay MR and its normal contact, wires 99, 100 and 101, cam starter magnet LCS, and wire 102 to the negative bus 76.

The penalty relay PR is normally energized by four circuits which may be traced as follows:—Beginning at the positive bus 75, in multiple, wire 103, distance contacts 59¹, wires 104 and 105, distance contacts 59, wires 106 and 107 to wire 108: or contact finger 156 of MR in normal position, and wires 157 and 107 to wire 108; finger 109 of the relay PR and its front contact, wires 110 and 111, winding of relay PR, and wires 112 and 113, and then in multiple; wire 114, finger 115 of relay LR and its front contact, and wire 116 to wire 117: or, wire 168, contacts 72 and wire 167 to wire 117; speed-distance contacts 56, and wire 118 to negative bus 76.

The electro-pneumatic valve EPV is normally energized by two circuits as follows:—(1) Beginning at the positive bus 75, wires 120 and 121, distance contacts 73, wires 122, 123 and 124, finger 125 of relay PR and its front contact, wire 126, valve EPV, and wire 127 to the negative bus 76; (2) beginning at the positive bus 75, wires 120 and 121, contact 73, wires 122 and 164, contact 74, wires 163 and 165, back contact 160 of relay AR, wires 166 and 124, front contact 125 of relay PR, wire 126, winding of the E. P. V., wire 127 to the negative bus 76. The second circuit just traced is, however, a moot circuit because the functioning of contacts 74 and 160 produce no effect as far as the circuit in question is concerned, because these contacts are shunted by the wire.

Maximum speed limit.—While the train is traveling under a clear or proceed signal in a clear block, a predetermined maximum speed limit is imposed and the brakes are automatically applied if the train exceeds this speed limit. Referring to Fig. 3, with the permissive speed cam 50 in its initial position, if the running speed of the train exceeds a certain value, assumed to be 60 miles per hour, the lower end of the floating lever 51 is moved so far to the left as to cause opening of the contacts 56 which break the energizing circuit for the penalty relay PR. Upon de-energization of the penalty relay PR, its front contact

125 opens and de-energizes the valve EPV, thereby automatically applying the brakes. The penalty relay PR can not again be energized until the train has been brought substantially to a stop to close the speed contacts 69 whereupon a pick up circuit for the relay PR is established as follows:—Beginning at the positive bus 75, wires 130 and 131, two mile per hour speed contacts 68—69, wire 132, finger 133 of relay LR and its front contact, wires 134 and 111, winding of relay PR, and wires 112, 113 and 114 through contact 115 of relay LR, wires 116 and 117, speed distance contacts 56 and wire 118 to the negative bus 76 as in the normal closed energizing circuit for the relay PR above traced.

In the particular arrangement shown, therefore, the train is brought to a stop whenever the maximum speed limit is exceeded, thereby in effect penalizing the engineer for exceeding the speed limit. This penalty, however, is optional; it should also be understood that the system preferably includes a suitable warning signal which is given when the speed of the train approaches the maximum speed limit.

Caution block.—When the train enters a caution block, or passes a corresponding control point, the contact fingers of the main car relay MR are reversed, extinguishing the lamp G and lighting the lamp Y, (wire 135 and reverse contact of finger 87), and also de-energizing the starter magnet HCS, while maintaining the cam starter magnet LCS energized (through wire 136 and reverse contact of finger 98). The de-energization of the cam starter magnet HCS connects the distance shaft 36 to the car wheels, and in addition to starting the gradual movement of the permissive speed cam 50, also rotates the actuating discs of the distance contact units 59 and 70. Referring to Fig. 1, after the train has advanced a short distance into the caution block, say 200 feet, which is longer than the longest "dead-section" distance encountered on the railway, the contacts 70 close, as indicated by the change of the line 70 in Fig. 1 from dotted to a solid line. The closure of these contacts 70 establishes a circuit for energizing the acknowledging signal as follows:—Beginning at the positive bus 75, wires 141, 142 and 143, contacts 70, wires 144 and 145, contact 64 of the contactor AC, wire 146, acknowledging signal B, and wire 147 to the negative bus 76.

The magnet 66 is also energized over wires 148 and 149. The sounding of the acknowledging signal B is a warning to the engineer to operate the acknowledging contactor; and assuming that the engineer is vigilant and does acknowledge by moving the plunger 61 to its lower position, the opening of the contacts 64 stops the acknowledging signal, and the closing of the contacts 63 sets up an energizing circuit for the acknowledging re-

lay AR as follows:—Beginning at the positive bus 75 wires 141 and 150, contact 63 of acknowledging contactor AC, now closed, wire 151, relay AR, and wire 152 to the negative bus 76.

The plunger 61 is held in its lower position by the magnet 66. After a further distance of travel, sufficient to afford reasonable time for the engineer to acknowledge, the contacts 59 open, as indicated by the line 59, in Fig. 1. The opening of these contacts 59 makes a break in the normal energizing stick circuit for the penalty relay PR; but since the engineer is assumed to have acknowledged, the front contact 154 of the acknowledging relay AR is closed, supplying current from the bus 75 to the wire 108 over wires 153 and 155 in spite of the opening of the contacts 59, thereby maintaining the penalty relay energized.

If the engineer fails to acknowledge, the opening of the contacts 59 de-energizes the penalty relay PR which in turn de-energizes the valve EPV thereby applying the brakes, and maintaining them applied until the train is brought to a stop as indicated by the curve 78 in Fig. 1, whereupon the penalty relay is re-energized by the closure of the speed contacts 69 in the same way as previously explained. But regardless of acknowledgement, speed restriction is enforced, in accordance with speed distance curve 57, by the cam 54.

The contacts 59 remain open for only a short distance of travel, (see Fig. 1), and after closure thereof, the contacts 70 open, de-energizing the magnet 66 and releasing the plunger 61 which is restored by the spring 62 to its upper normal position.

As the train advances through the caution block, the permissive speed cam 50 is gradually turned and enforces successively lower speed limits. If at any point in the travel of the train its running speed exceeds the permissive speed, the contacts 56 open, de-energizing the penalty relay PR and in turn the valve EPV, applying the brakes and maintaining the brakes applied until the train is brought substantially to a stop and the penalty relay PR is again energized. Consequently, the engineer must maintain the speed of his train below the permissive speed curve 57 shown in Fig. 1, or else the brakes are automatically applied, and as a penalty, the train must be stopped before the brakes can be released.

After the train has advanced to a predetermined point, indicated by a break in the lines 59 and 70, the contacts 70 are again closed, and again the contacts 59 open, compelling acknowledgment in the same way as previously explained. The point in the block, at which the contacts 59 open is preferably braking distance for the minimum speed from the exit end of the block, so that if

the engineer is incapacitated, or for any other reason fails to acknowledge, the resultant brake application will stop the train before the train reaches the exit end of the block, as indicated by the curve 76 in Fig. 1. As shown, the permissive speed cam 50 is assumed to have reached its minimum speed position at the point indicated by the vertical line 77 in Fig. 1, some distance in the rear of the point at which the contacts 59 open; but, if desired, the parts may be constructed and proportioned to cause the permissive speed cam 50 to assume its minimum speed position at, or a small distance in the rear of, the point at which the contacts 59 open.

If the block should change from a caution block to a clear block at any time, the contact finger 87 of the main car relay MR assumes the normal position (shown by a heavy line) changing the cab signal indication from caution to proceed, and re-energizing the cam starter magnet HCS. The shaft 36 is returned to its initial position by the spring 48, and during such return movement of the shaft 36, the contacts 59 are opened momentarily; and while the penalty relay PR may be made sufficiently slow acting to avoid its improper operation by such momentary opening of the contacts 59, it is preferred to provide an auxiliary circuit, including wire 157 and normal contact and finger 156 of the relay MR to supply energy to the wire 107 and to maintain the penalty relay PR energized in spite of the opening of the contacts 59.

In order that the engineer may not be able to defeat the objects of the invention by permanently fastening or holding down the acknowledging contactor AC, the finger 95 and its back contact of the acknowledging relay AR, are included in the energizing circuit for the cam starter magnet HCS, so that, if the engineer should keep his acknowledging contact AC depressed, and the relay AR energized, the cam shaft 36 is run down and maintained in its minimum speed position. Consequently, the engineer will not fasten down the acknowledging contactor AC in order to avoid acknowledging the caution indication, because by so doing he restricts the speed to a minimum.

Danger block.—As the train passes from a caution to a danger block, the shaft 36 is in its extreme position and is held there, the pinion 43 rotating idly in the mutilated portion 46 of the gear 45. As the train passes into the danger block, the car relay MR is de-energized and its contact fingers assume the neutral or middle position, de-energizing the cam starter magnet LCS and starting in rotation the distance shaft 37. Referring to Fig. 1, after a short distance of travel of the train, longer than "dead-section" distance, the contacts 71 close giving the acknowledg-

ing signal B and energizing the magnet 66. After a further distance of travel, the contacts 59¹ and 72 open, and unless the engineer has acknowledged and brought about closure of the front contact 154 of the acknowledging relay AR, the penalty relay PR is de-energized, with the same result previously pointed out. The purpose of the contact 72 is pointed out under the heading "absolute stop".

This acknowledgment just beyond the entrance to a danger block is to some degree superfluous for the first stop signal, inasmuch as it merely supplements the acknowledgment required near the end of the preceding caution block. The acknowledgment just described, however, is desirable to assure acknowledgment by the engineer of each successive stop signal. It will be evident that, before a train can pass a stop signal and enter a danger block, it must be in a caution block, because the caution control current will be applied to the track rails under such train sometime before the track ahead becomes clear to permit the train to advance by the stop signal. Consequently, after a train has passed one stop signal and entered into a danger block, except for the case of interlocked territory as for example, block K of Fig. 2, it cannot pass a second stop signal until the block it is in, formerly a danger block, has for a short distance of travel at least, changed to a caution block. During this change to a caution block, the cam starter magnet LCS is re-energized, restoring the distance shaft 37 to its initial position; and as the train passes the second stop signal and advances into a danger block again, this distance shaft 37 is again set into operation and the opening of its contacts 59¹, forces acknowledgment. During the return of the shaft 37, the penalty relay PR is prevented from dropping upon momentary opening of the contacts 59¹ by reason of the fact that the relay MR will first have assumed, say, the reverse or caution position, under which condition current is applied to the wire 105 through the wire 158 and the reverse contact and finger 156 of the car relay MR.

When the train enters a danger block, after a short distance of travel longer than dead-section distance, the shaft 37 is turned to the point where the distance contacts 73 open, breaking the normal energizing circuit for the valve EPV, heretofore traced, and making the energization of the valve EPV dependent upon the speed contacts 34-35 (closed only at and below the minimum speed of 15 miles per hour), the distance contacts 74, and the finger 160 of the acknowledging relay AR and its back contact, the energizing circuit for the valve EPV under these conditions being traced as follows:—Beginning at the positive bus 75, wires 120 and 161, minimum speed contacts 34-35, wire 162, and

thence either along wire 163 through distance contacts 74 and wires 164 and 123 to the wire 124, or through wire 165, finger 160 of relay AR and its back contact, and wire 166 to the wire 124, and thence through the front contact 125 of the penalty relay PR, wire 126, valve EPV, and wire 127 to the negative bus 76.

On account of this circuit arrangement, 10 after the train has traveled a short distance into a danger block, the valve EPV is automatically de-energized whenever the running speed of the train exceeds the selected minimum speed limit; but since the minimum 15 speed limit in question is already enforced by the cam 50 in its extreme position, the control of the valve EPV provided by the minimum speed contacts 34-35 is merely incidental to the desired control through a danger 20 block and is employed more particularly for protection against open switches and the like, as will presently be described.

The multiple branches in the circuit for the valve EPV just traced through the distance contacts 74 and back contact 160 of the relay AR are provided in order to protect the acknowledging contactor AC against abuse while the train is in a danger block. The contacts 74 open after a distance of travel sufficient 25 to complete the acknowledging operation and after the relay AR has become de-energized. If the engineer, however, instead of releasing the acknowledging contactor AC and permitting it to return to normal, should 30 attempt to avoid the acknowledgment of the next stop signal by holding or fastening down the acknowledging contactor AC, then the back contact 160 of the relay AR remains open, whereupon the valve EPV is de-energized 35 upon opening of the distance contacts 74.

Open switch and siding protection.—If a switch should be opened ahead of a train in the same block, or a rail break, the car relay 40 MR at once assumes its de-energized position. Similarly, if a train passes from a siding into an occupied block on the main track, the main car relay MR, if energized, is at once de-energized, and if de-energized, remains in 45 its de-energized condition.

Referring to Fig. 4, whenever the car relay MR assumes its de-energized position, the cam starter magnet LCS is de-energized; and after a short distance of travel to take care 50 of dead-sections, the distance contacts 73 open, breaking the normally closed shunt around the minimum speed contacts 34-35, and rendering these minimum speed contacts effective to control the valve EPV, as above 55 described, so that if the speed of the train at this time is more than the minimum speed of 15 miles per hour, the valve EPV is de-energized and the brakes applied. Accordingly, whenever the main car relay MR assumes its 60 de-energized position, the minimum speed

limit is at once set up after a very short distance of travel, say 150 feet, and it is not necessary to run down the permissive speed cam 50 to its minimum speed position. Hence, when a train comes out from a siding onto a main track into a danger or occupied block, the minimum speed limit is at once imposed, irrespective of the position of the permissive speed cam, which may be in different positions depending on how the train 71 moved into the siding.

Absolute stop.—At certain points along the railroad, such as at drawbridges, crossings, and points of converging or conflicting routes, it is desirable to provide an absolute stop control for trains. Such points are usually protected by so-called stop-and-stay, or absolute signals; and on many railroads derails are also provided. For an adequate absolute stop control, it is desirable to compel 76 an approaching train to reduce its speed, and at or near the absolute signal or corresponding point of control, apply the brakes automatically irrespective of the speed of the train as it passes such signal or control point, such brake application being beyond the power of the engineer to prevent, by acknowledging or otherwise.

Referring to Fig. 2, the signal ZA at the exit end of the block K is assumed to be an absolute stop signal which is controlled in accordance with established practice, wholly manually, or partly manually and partly automatically. Since the particular means that may be employed to control this absolute stop signal ZA may take various forms and is not material to the present invention, no attempt has been made to illustrate any particular organization of circuits and devices for providing the required control for this signal. 100 In the block K, in the rear of the absolute stop signal ZA, the track phase or loop circuit current is supplied to the track rails in the same way as in block signal territory, as shown and described in connection with Fig. 1. The line phase or simplex circuit current is controlled in different ways dependent upon the position of the signal ZA. A circuit controller 15, assumed to be operated by movement of the signal ZA, or by its controlling lever, or by equivalent means, is in the position shown with the signal ZA in its stop position, supplying line phase or simplex circuit current between the resistances 7² and 14 of the block K only; whereas with this signal ZA in its caution or clear position (assuming a 3-position signal), the circuit controller 15 is shifted to supply line phase current between the resistances 7² and 8² of the block K, that is, throughout the length of this block. A pole changing circuit controller 16, assumed to be operated by the signal ZA or controlled by equivalent means, governs the instantaneous polarity of the line phase current with respect to the track phase current. signal ZA in the stop position shown, the pole changing circuit controller 16 is in the position shown and reverses the instantaneous polarity of the line phase current, so as to cause the car relay on a train traveling in the block K to assume its reverse position. With the signal ZA in the caution or clear position, the circuit controller 16 assumes its other position, providing normal polarity of line phase current.

Assuming the signal ZA to be in its stop position, when a following train enters the block K, its car relay MR is reversed with the same effect as previously explained. If the engineer fails to acknowledge, the brakes are applied and the train brought to a stop, as indicated by the curve 78; and even if the engineer does acknowledge, he is obliged to keep the running speed of his train at all times below the permissive speed curve 57, otherwise the brakes are automatically applied. When the locomotive passes the resistance 14, the main car relay MR assumes its de-energized position, and also the line phase relay LR on the car is de-energized, since from the resistance 14 to the exit end of the block K the line phase current is cut off. The de-energization of the relay MR starts the distance shaft 37, opening the acknowledging contacts 59¹ and 72 the same as when a train passes into a danger block. Similarly, the contacts 58 and 70 are operated as the shaft 36 assumes its extreme position, the same as near the exit end of a caution block. The resistance 14 is preferably so located with respect to the run-out distance of the cam shaft 36 as to cause the contacts 59 and 59¹, and also contacts 70 and 71, to be shifted at about the same time. The operation of these contacts gives the acknowledging signal and applies the brakes if the engineer fails to acknowledge, the same as previously explained.

So far considered, the operation upon approaching the absolute stop signal ZA is the same as that occurring upon the approach to a permissive stop signal in block signal territory. In the case of the absolute stop signal, however, the line phase relay LR is de-energized, releasing its contact fingers 115 and 133 to open their front contacts. The opening of the front contact of the finger 133 interrupts the pick-up circuit for the penalty relay PR which includes the low speed contacts 68 and 69, so that once the relay PR is de-energized to apply the brakes, it cannot again be energized to permit release of the brakes even though the train is brought to a stop. At a predetermined point near the exit end of the block K, preferably and assumed to be braking distance for the minimum speed from the actual exit end of this block, the contacts 72 are opened, as indicated in Fig. 2, breaking the shunt (including wires 167 and 168) around the contact finger 115 and front contact of the relay LR.

Consequently, if a train advances beyond the point at which the contacts 72 are open, the relay LR being de-energized, the penalty relay is de-energized, and the brakes applied. The point at which the contacts 72 open, therefore, becomes the point of absolute stop control in the event the line phase relay LR is also de-energized. As shown, this point is a short distance in the rear of the signal ZA; but if it is desired to permit the locomotive to advance all the way up to the signal ZA, as ordinarily done, the signal ZA may be located opposite the point at which the contacts 72 open, or the resistance 14 may be so located that the point at which the contacts 72 open is at or beyond the absolute stop signal ZA and the insulated joints defining the exit end of the block K, provision being made to cut off line phase current for a short distance in the next block L.

The train must stop at the signal ZA in its stop position until this signal is cleared, whereupon the circuit controller 15 is shifted to supply line phase or simplex current throughout the length of the block K and energize the relay LR. The re-energization of the relay permits restoration of the penalty relay PR and release of the brakes. If the signal ZA is cleared to the caution position, the cam starter magnet LCS only is energized, and the distance shaft 37 restored to the normal position, the minimum speed limit being maintained during the further advance of the train on account of the cam 50 being in its minimum speed position. If, however, the signal ZA is cleared to the proceed position, the car relay MR is restored to its normal position, both of the cam starter magnets LCS and HCS are energized, and the car apparatus is restored to the normal condition in the manner previously explained. In conformity with recognized interlocking practice, it may be desired to employ a "call-on" signal in conjunction with the signal ZA and permit a train to advance beyond the signal ZA in its stop position at restricted speed. This is easily accomplished by making provision for shifting the circuit controller 15 upon operation of the "call-on" signal, so that the train may advance without absolute stop control past the signal ZA. It will be evident that other adaptations and modifications may be made to incorporate, with the absolute stop train control arrangement shown, other features of interlocking practice.

Non-Control territory.—It will be evident that in the system of this invention, current must be applied to the track rails to permit a train to proceed. In the practical application of a train control system to railroads, however, certain portions of track, such as sidings, branch lines, and the like, may not be equipped to provide train control current, such portions of track constituting non-con-

trol territory. In order to permit the train to travel over such non-control territory, special means is provided to permit cut-out of the automatic control as the train enters such territory and for automatically reinstating train control upon re-entering regular control territory. The form of this means herein disclosed is the same as that shown and described in other applications which I have filed; and no claim is made herein specifically to this control in non-control territory.

At the entrance to non-control territory a short section of track is preferably equipped so as to cause the car relay MR always to assume its normal position. As the train travels over this short section of track, the engineer is supposed to operate the acknowledging contactor AC, being guided by a marker along the track or equivalent means, thereby establishing a circuit for energizing the non-control relay NC which may be traced as follows:—Beginning at the positive bus 75, wire 170, finger 171 of relay MR in the normal position, wires 172 and 173, finger 174 and its front contact of the acknowledging relay AR, wires 175 and 176, relay NC and wire 177 to the other bus 76.

As the train proceeds into non-control territory, the relay MR is de-energized, thereby establishing a stick circuit for the relay NC, NC not dropping while finger 171 moves from normal to neutral positions, as follows:—Beginning at the positive bus 75, wire 170, finger 171 of relay MR and its neutral contact, wire 178, finger 179 of relay NC and its front contact, wires 180, 181 and 176 relay NC and wire 177 to the other bus 76. The contact AC is then released to de-energize the AR relay.

Thus, the relay NC is energized, due to acknowledgment, upon entrance to the non-control territory, and is maintained energized, by being stuck up, while the train travels through this non-control territory. The relay NC, while energized, performs several functions. The attraction of its finger 179 interrupts the circuit through the danger or low speed lamp or indicator R, and in addition to establishing the stick circuit for the relay NC, supplies current to energize a lamp or indicator W, which serves to remind the engineer that he is running in non-control territory. The attraction of the finger 90 establishes a circuit, including wires 130, 183 and 184, for energizing the cam starter magnet HCS; and the attraction of the finger 182 establishes a similar circuit, including wires 185 and 186, for energizing the cam starter magnet LCS. The attraction of the finger 188 establishes a connection from one terminal of the penalty relay PR over wires 112, 187 and 189 to the negative bus 76, so as to maintain the relay PR energized in spite

of the opening of the speed-distance contacts 56.

When the train re-enters regular train control territory, the car relay MR is energized, either normal or reverse, preferably the latter by the regular train control current, or by current especially supplied irrespective of traffic conditions over a short section at the entrance to train control territory; and when the car relay is energized, the stick circuit for the relay NC is interrupted and this relay is deenergized, reinstating regular train control.

In order to permit the train to proceed in case of a sudden failure of power, or under other conditions where the NC relay has not been energized in the usual way, an emergency contactor in the form of a push button 67 is provided to permit energization of the relay NC. This push button 67 is safeguarded in some appropriate manner, as by being locked or sealed, or provided with a counter, so that it cannot be abused by the engineer without detection.

Various adaptations or modifications may be made in the particular embodiment of the invention shown. The acknowledgment at the caution signal may be omitted, by leaving off the notches on the actuator cams operating the contacts 59 and 70 shortly after the cam shaft 36 starts. The penalty for exceeding the permissive speed limit may be omitted by including the speed-distance contacts 56 directly in the energizing circuit for the valve EPV, rather than in the circuit for the penalty relay PR. Similarly, the contact finger 115 of the relay LR, and the distance contacts 72, may be included directly in the energizing circuit for the valve EPV rather than in the circuit for the penalty relay PR. In short, the particular circuit organization shown may be adapted to omit or modify some of the functions described.

The modification of Fig. 5.—Reviewing the general organization and operation of the embodiment of the invention hereinbefore discussed, one feature relates to the provision of means for automatically applying the brakes at a predetermined point in the rear of a stop signal unless the engineer acknowledges. In order to obtain this desired control at the desired point, the arrangement of Fig. 1 employs distance contacts operated by the permissive cam shaft 36 for enforcing the acknowledgment of the stop signal, this arrangement requiring starting of the cam shaft 36 at a predetermined run-out distance in the rear of the acknowledging point. In the modification of Fig. 5, the acknowledgment for the stop signal is obtained by de-energizing the main car relay MR at a predetermined point, conveniently referred to as the "B" point, at a distance in the rear of the signal sufficient to cover the "dead-section" distance and braking distance for the minimum speed.

Since it is necessary, in the form of the invention shown, to maintain line phase or simplex circuit current throughout the blocks in block signal territory, in order to avoid an absolute stop, the de-energization of the relay MR 5 is obtained at the "B" point in Fig. 5 by cutting off the track phase or loop circuit current for a short distance near the exit end of each caution block.

Referring to Fig. 5, the equipment for a 10 block N, assumed to be next in the rear of an absolute stop signal ZA, has been shown complete together with the equipment for a portion of an adjacent block M. Although many of the parts are similar to those shown in Fig. 15 1, for convenience different reference numbers are employed. Each block is made up of two track sections, the block N having insulated joints 190 at the point "B" forming a short track section N^a at the exit end of the 20 full block. The first or rear section of each block, between the entrance and the point "B", has a track relay 191 and a track battery 192, and is permanently supplied with 25 track phase or loop circuit train control current by a transformer 193, having its secondary in series with the track battery 192 and its primary energized by a line transformer 194. The short section at the exit end of each block, 30 from the point "B" to the exit end of the block, is equipped with a track relay 195 and a track battery 196. A transformer 197 has its secondary in series with the track battery 196 and its primary energized from a line transformer 198, this primary circuit also 35 including the contact finger 199 and front contact of a line relay 200. This line relay 200 has an energizing circuit which includes front contacts 201 and 202 of the two track relays 191 and 195 of the next block in advance. 40 Line phase current is constantly supplied to the rear section of the block between resistances 203 and 204 from the line transformer 205 said current being of one relative instantaneous polarity or another depending upon 45 the position of pole changing contact fingers 206 and 207 operated by the corresponding line relay 200.

In automatic block signal territory, represented by the block M, line phase current is 50 permanently supplied to the second or advance section of each block (section M^a) between the resistances 208 and 209 from a line transformer 210. In the block N in the rear of the absolute stop signal ZA, however, the line phase current for the section N^a, between the resistances 208 and 209, is controlled by a 55 circuit controller 211, which in this instance is assumed to be associated with the interlocked lever controlling the signal ZA.

The car apparatus for Fig. 5 may be the same as that shown in Fig. 4, except that the projections and recesses on the actuators for the distance contacts 59 and 70, which result 60 in the operation of these contacts when the

cam shaft 36 nearly reaches its extreme position are omitted.

Referring to Fig. 5, when a train enters a caution block in block signal territory, the same operation hereinbefore described takes place to require the engineer to acknowledge the caution signal; and at the point "B" in this block the distance shaft 37 is started and through the operation of contacts 59¹ and 71 requires the engineer to acknowledge the danger signal. In Fig. 5, however, there is only one acknowledgment for the first stop signal required, that due to the opening of the contacts 59¹ after a travel beyond the point "B" of dead-section distance.

With the absolute stop signal ZA in the stop position, a train traveling through the block M is required to acknowledge the caution signal, reduce speed, and acknowledge the stop signal the same way as in the arrangement shown in Fig. 1. Since the signal ZA is in the stop position and the circuit controller 211 open, there is no line phase current for the section N^a, and the relay LR is de-energized, so that if the train advances beyond the point where the distance contacts 72 open, an absolute stop is enforced.

The modification of Fig. 5 provides for enforcement of acknowledgment of successive stop signals but in a somewhat different manner than in the arrangement of Fig. 1. In Fig. 1, as previously explained, succeeding stop signals are acknowledged at a point dead-section distance beyond the signal where the distance contacts 59¹ open (see Fig. 1); whereas in Fig. 5, the acknowledgment of each stop signal, whether the first or a succeeding stop signal, takes place at the same point, namely, dead-section distance beyond the point "B" in each block. In the arrangement shown in Fig. 5, when a train passes from a caution block into a danger block, both of the shafts 36 and 37 are in the ultimate operated position. If the forward train in the danger or occupied block is beyond the point "B", as soon as the following train passes into this danger or occupied block, the main car relay MR is energized to move its fingers to the reverse position, restoring the shaft 37 to its initial position, but leaving the shaft 36 in its run-out position to maintain the continuing minimum speed limit. When the following train passes the point "B", and the next signal in advance is at stop, or the intervening section occupied by another train ahead, the main car relay is again de-energized, starting rotation of the shaft 36 and requiring the engineer to acknowledge. If it should happen that, when the following train enters the danger or occupied block, the forward train is in the rear of the point "B", then the main car relay MR remains de-energized. At some point in the travel of the two trains, however, the car

relay MR on the following train is energized reversely, since there is some instant when the wheel shunt of the forward train is removed to permit the track phase current to be supplied to the following train. Such energization of the car relay restores the shaft 37 and conditions the apparatus to enforce acknowledgment of the next signal if at stop.

10 The specific embodiments of the invention shown and described are selected for illustrative purposes; and it should be understood that various changes, additions, modifications, and adaptations may be made without departing from the invention.

What I claim is:—

1. Car-carried apparatus for automatic train control systems of the type in which a car-carried relay is maintained energized in response to current flowing in suitable trackway circuits under clear traffic conditions ahead, such circuits extending through the whole trackway except for short distance intervals at dead sections, a brake setting device, a speed responsive device, a distance device normally in its inactive condition but initiated upon a cycle of operation when traffic conditions change from clear to caution as manifested by said relay, means governed by said distance device for gradually setting up decreasing speed limits and for actuating said brake setting device if the actual speed of the vehicle exceeds such permissive speed, and another distance device normally in an inactive condition and initiated when the train enters a danger zone, said another distance device abruptly setting up a predetermined low speed limit when the train has traveled more than the maximum dead section distance after this distance device has been initiated.

2. Car-carried apparatus for automatic train control systems of the type in which a car-carried relay is maintained energized in response to current flowing in suitable trackway circuits under clear traffic conditions ahead, such circuits extending through the whole trackway except for short distances at dead sections, a delayed action device normally held in an inactive condition by a three-position relay which is maintained energized by currents flowing in said trackway circuits, a single element relay normally maintained energized in response to currents flowing in one of said trackway circuits, and means for stopping the train regardless of the speed thereof if the single element relay is in a deenergized position when said delayed action device has changed a predetermined degree from normal.

3. Car-carried apparatus for automatic train control systems of the type in which a car-carried relay is maintained energized in response to current flowing in suitable trackway circuits under clear traffic conditions

ahead, such circuits extending through the whole trackway except for short distances at dead sections, a delayed action device normally held in an inactive condition by a three-position relay which is maintained energized by currents flowing in said trackway circuits, a single element relay normally maintained energized in response to currents flowing in one of said trackway circuits, and means effecting an automatic brake application if the engineer does not manifest his vigilance if a train travels more than a predetermined distance with said three-position relay deenergized, and means for effecting an automatic application of the brakes if the train travels a predetermined distance with both the three-position relay and the single element relay deenergized regardless of whether or not the engineer manifests his vigilance.

4. Car-carried apparatus for automatic train control systems of the type in which a car-carried relay is maintained energized in response to current flowing in suitable trackway circuits under clear traffic conditions ahead, such circuits extending through the whole trackway except for short distances at dead sections, a delayed action device normally held in an inactive condition by a three-position relay which is maintained energized by currents flowing in said trackway circuits, a single element relay normally maintained energized in response to currents flowing in one of said trackway circuits, and means for effecting an automatic brake application if the engineer does not manifest his vigilance if the train travels a predetermined distance with said three-position relay in the reversed or the de-energized position, and means for effecting an automatic brake application regardless of the engineer's manifestation of his vigilance if said train travels said predetermined distance with the single element relay deenergized.

5. Car-carried apparatus for automatic train control system of the continuous inductive three position type in which the trackway is provided with circuits for conducting train control current at all points except for short distances at dead sections comprising, a permissive speed device normally in its maximum permissive speed condition which if initiated gradually sets up more restrictive permissive speed limits in accordance with the progress of the train along the track and which is initiated upon entrance of the train into caution territory, an actual speed device for ascertaining the speed at which the car is traveling, a brake setting device, a delayed action device normally in inactive condition and initiated upon the entrance of the train into danger territory and which sets up a minimum speed limit when the train has traveled more than the maximum dead section distance, and means for automatically

actuating said brake setting device if the actual speed is higher than the lowest permissive speed set up by either the permissive speed device or the delayed action device.

6. Car-carried apparatus for automatic train control systems of the continuous inductive three-position type in which the trackway is provided with circuits for conducting train control current at all points except for short distances at dead sections comprising, a permissive speed device normally in its maximum permissive speed condition which if initiated gradually sets up more restrictive permissive speed limits in accordance with the progress of the train along the track and which is initiated upon entrance of the train into caution territory, an actual speed device for ascertaining the speed at which the car is traveling, a brake setting device, a delayed action device normally in inactive condition and initiated upon the entrance of the train into danger territory and which sets up a minimum speed limit when the train has traveled more than the maximum dead section distance, means for automatically actuating said brake setting device if the actual speed exceeds the lowest permissive speed set up by either the permissive speed device or the delayed action device, and other means for automatically actuating said brake setting device under predetermined conditions ahead regardless of the speed of the train.

7. Car-carried apparatus for automatic train control systems of the type in which a car-carried relay is maintained energized in response to current flowing in suitable trackway circuits under clear traffic conditions ahead, such circuits extending through the whole trackway except for short distances at dead sections, a three-position relay adapted to assume a position dependent on the character of the current flowing in a plurality of trackway circuits, a single element relay dependent for its energization upon the flow of current in one of said trackway circuits and means for applying the brakes of the train if the train has traveled a predetermined distance with the three-position relay deenergized and the single element relay is in its deenergized position.

8. An automatic train control system of the three-position continuous inductive type comprising; a trackway having alternating current flowing in suitable circuits located along the same throughout train control territory except for short distances at points designated dead sections and of car-carried apparatus including, a permissive speed device normally assuming a maximum permissive speed condition which is initiated upon the entrance of the train into caution territory and which if initiated gradually sets up lower permissive speed limits in accordance

with the progress of the train along the track, a speed device, a brake setting device acting on the usual air brake system, a delayed action device which is initiated upon entrance of the train into danger territory and means for actuating said brake setting device if the speed of the train as manifested by said speed responsive device is higher than the lowest permissive speed set up by said permissive speed device and said delayed action device.

9. An automatic train control system comprising means partly on the vehicle and partly along the trackway for continuously transmitting influences corresponding to traffic conditions ahead to the vehicle, car-carried apparatus comprising means responsive to said influences for manifesting said traffic conditions ahead, a delayed action device, delayed in accordance with the progress of the vehicle along the trackway and initiated upon the manifestation of adverse traffic conditions ahead, an acknowledging device having an active and an inactive position, means for effecting an automatic brake application if the acknowledging device does not assume its active position when said delayed action device has changed a predetermined degree from normal and for effecting an automatic brake application if said acknowledging device does not assume its active position when said delayed action device has changed a larger degree from normal.

10. An automatic train control system comprising, means partly on the vehicle and partly along the trackway for manifesting on the vehicle conditions of traffic existing ahead of the vehicle, a delayed action device delayed in accordance with the progress of the vehicle along the trackway and initiated upon the manifestation of adverse traffic conditions ahead, an acknowledging device having an active and inactive position, means for effecting an automatic brake application if the acknowledging device does not assume its active position when said delayed action device has changed a predetermined degree from normal and for effecting an automatic brake application if said acknowledging device does not assume its inactive position when said delayed action device has changed a larger degree from normal.

11. An automatic train control system comprising, means partly on the vehicle and partly along the trackway for manifesting on the vehicle conditions of traffic existing ahead of the vehicle, a delayed action device normally maintained inactive which if initiated changes in accordance with the progress of the vehicle along the trackway, and which if changed to a predetermined extent sets up a low permissive speed limit which the vehicle cannot exceed without incurring an automatic brake application, an acknowledging device having an active and an inac-

tive position, and which is normally in its inactive position, means for effecting an automatic brake application regardless of the speed of the train if the acknowledging device is not in its active position when the delayed action device has changed to a predetermined extent, and means for effecting an automatic brake application if the acknowledging device is not in its inactive position when said delayed action device has changed to a slightly greater extent.

12. In an automatic train control system, a three-position relay on the vehicle controlled in accordance with traffic conditions ahead by means of a plurality of trackway circuits, a two-position car relay controlled by one of said trackway circuits, said trackway circuits being energized in accordance with traffic conditions ahead, means controlled by said three-position relay for imposing increasingly restrictive speed limits under certain unfavorable traffic conditions ahead, and means controlled by said two-position relay for imposing an automatic brake application to bring the vehicle substantially to a stop under certain other unfavorable traffic conditions ahead.

13. In a train control system, car-carried apparatus, comprising, a train control device, means initiated by track-way influences for imposing a tapered speed limit on the train, a second means initiated by different track-way influences and effective after a moment of delay to abruptly impose a predetermined fixed low speed limit on the train, and means for initiating the train control device if the train speed exceeds said speed limits.

14. Car-carried apparatus for automatic train control systems of the type in which a car-carried relay is maintained energized in response to flow of track-way current flowing under clear traffic conditions ahead, extending through the entire track-way except for short distances at dead sections, a first relay adapted to assume a position depending on the instantaneous relative polarity of the currents flowing in the track-way, a second relay depending for its energization upon the flow of current in said track-way, and means for applying the brakes of the train after the train has traveled a predetermined distance with the first relay de-energized if the second relay is in its deenergized condition.

55 In testimony whereof I affix my signature.
WINTHROP K. HOWE.
